APPARATUS FOR TREATING PETROLEUM DISTILLATES

Robert E. Burk and Everett C. Hughes, Cleveland,
Ohio, assignors to The Standard Oil Company,
Cleveland, Ohio, a corporation of Ohio

Application March 9, 1936, Serial No. 67,904

1 Claim. (Cl. 196—46)

This invention relates to treating-apparatus, and more particularly apparatus for treating petroleum distillates with alkaline sulphur-removing media; and it is among the objects of the invention to provide equipment capable of maintaining equilibrium in the system without close supervision by technical operators. Other objects and advantages will appear as the description proceeds.

To the accomplishment of the foregoing and related ends, the invention, then, comprises the features hereinafter fully described, and particularly pointed out in the claim, the following description and the annexed drawing setting forth in detail certain illustrative embodiments of the invention, these being indicative however, of but a few of the various ways in which the principle of the invention may be employed.

In said annexed drawing the sole figure is a semi-schematic elevational view of apparatus embodying the invention.

Referring more particularly to the drawing, there is shown a series of chambers 2, 3, 4, in which the petroleum distillate is washed progressively with the alkaline sulphur-removing media, as for instance a caustic soda solution, the distillate entering the system through connection 5, and thence passing from the mixing chamber 2 by a connection 6 to chamber 3, and thence by a connection 7 to chamber 4, being successively subjected to mixing with the alkaline medium, as caustic soda solution, and flowing off progressively to the next chamber in the series, a constant inter-face level as the inherently immiscible liquids separate being maintained in each chamber by a suitable means such as a float 10 having a link 11 pivoted at 12 to the lever arm 13 of an over flow valve 14 on the distillate connection. From the final treating chamber 4, a connection 15 may lead to a water-washing chamber 16 in which water is supplied by connection 17 to intermix with the distillate and separate and be drawn off at 18, while the distillate is taken off at 19.

The caustic soda solution is moved generally counter-currently to the direction of flow of the distillate, and may be introduced by a connection 20 into the last treating chamber 4, from whence it passes by connection 21 back to treating chamber 3, and thence by connection 22 to a regenerating chamber 23, in which the caustic soda solution is mixed with a solution of elemental sulphur in an organic solvent, as benzol, aliphatic or naphthenic hydrocarbons, as set forth in United States Patent No. 2,009,954. The caustic

soda solution and the organic solution of sulphur are mingled counter currently to each other and being inherently immiscible, finally separate and are drawn off to their respective lines, the caustic soda solution passing through line 20 to the chamber 4, and the organic solution of sulphur circulating around through a connection 25, whose inlet is governed by a constant level valve 14, and the connection 25 leading through a sulphur-containing chamber 26 back to the mixing chamber 10 23. Desirably, two relay chambers for sulphur, 26 and 26' are provided, such that one can be replenished while the other is on the line, cutout valves being suitably arranged for this purpose.

The caustic soda solution proceeding counter currently against the distillate progressively becomes loaded up with mercaptides, and in the regenerating chamber 23 is then purified for recycling reusage. A progressive loss of causticity, although small, occurs, and this is proportionately replenished from a stock container 29. For this, we prefer to draw a determined amount by a pump 30 whose feed chamber 31 connects with the caustic soda supply 28 and discharges through the line 20 into the treating chamber 4 of the series. At the same time, the pump 30, which is of multiple character, proportionally pumps by its feed-chamber 32 an amount of regenerated caustic soda solution coming from the regenerator 23. At the same time, and in proportion, an amount of the used or spent caustic soda solution is drawn off from the end of its contact-series with the distillate, as by connection 34. This may be taken off through a control valve 35 providing a proportional draw off as rated against the input of fresh caustic soda from supply chamber 29. Or, preferably, the draw off of spent caustic solution is handled by the same pump 30 through its exhaust chamber 36, whereby the amount withdrawn is exactly in balance with the amount put into the system fresh from the supply chamber 29, through feed chamber 31.

With such equipment, distillates containing sulphur may be treated in automatic manner for removal of the objectionable sulphur compounds, and the treating system is at all times in a state of equilibrium, without hazard of disturbance of balance from input of fresh treating agent or withdrawal of spent agent.

Other modes of applying the principle of the invention may be employed, change being made as regards the details described, provided the features stated in the following claim, or the equivalent of such, be employed.

We therefore particularly point out and distinctly claim as our invention:—

In apparatus of the character described, the combination of a plurality of chambers in which 5 petroleum distillate may be mixed with a treating agent, a conduit leading from the top of each of said chambers through which the distillate is adapted to flow, a valve in each of said conduits for maintaining a constant level of distillate, a 10 passage leading from the bottom of each of said chambers, through which the treating agent is adapted to flow, a pipe to admit distillate and treating agent substantially in the middle portion of each of said chambers, a second plurality of 15 chambers containing means for regenerating said

treating agent after it has been used, one of said passages being connected to one chamber in said second plurality of chambers, and another of said passages leading to an exhaust chamber of a multiple pump, a container for fresh treating 5 agent and a feed chamber in said multiple pump for supplying fresh agent from said container to said first plurality of chambers, said feed chamber being actuated by a mechanism that actuates 10 said exhaust chamber whereby the input of treating agent is directly proportionate to the exhaust of same.
